Filed Oct. 26, 1973, Ser. No. 409,976

Term of patent 7 years

Int. Cl. D10—06

U.S. Cl. D10—110

FIG. 1 is a left side elevational view of an automobile parking guide showing my new design;

FIG. 2 is a rear elevational view thereof;

FIG. 3 is a front elevational view thereof, the extension arm being omitted for convenience of illustration;

FIG. 4 is a right side elevational view thereof, the actuating arm being rotated to a different position and the extension arm being omitted for convenience of illustration;

FIGS. 5 and 6 are respectively top and bottom plan views thereof;

FIG. 7 is a front elevational view of a second embodiment of my new design;

FIG. 8 is a left side elevational view thereof; and

FIG. 9 is a bottom plan view thereof.

The rear of the actuating arm of the second embodiment is identical to the rear of the first embodiment.

I claim:

The ornamental design for an automobile parking guide, as shown and described.
